UNITED STATES PATENT OFFICE.

ALFRED HENRY STOCKALL, OF BATH, ENGLAND.

PRINTER'S GALLEY FOR USE WITH THE MONO OR OTHER TYPE CASTING MACHINES.

1,038,018.

Specification of Letters Patent. Patented Sept. 10, 1912.

Application filed November 16, 1911. Serial No. 660,650.

To all whom it may concern:

Be it known that I, ALFRED HENRY STOCKALL, a subject of the King of Great Britain, resident of Bath, county of Somerset, England, engineer, have invented certain new and useful Improvements in Printers' Galleries for Use with the Mono or other Type Casting Machines, of which the following is a specification.

10 The invention relates to improvements in printers' galleries for use with mono or other type casting machines, as described in the following specification and illustrated in the accompanying drawings that form part of 15 the same.

15 The invention is an improvement following my former United States Patent No. 990,676 and it consists essentially in the novel construction and arrangement of 20 parts whereby the end gates are made interchangeable and are removably secured closing the ends of the gallery.

25 The objects of the invention are to devise a gallery which will allow the type to be passed in at either end as it is cast, thus facilitating the work of handling the type and obviating the necessity of transferring it to another gallery, and to devise a simple form of gallery the end gates of which will be self 30 locking and interchangeable, end for end.

35 In the drawings, Figure 1 is a perspective view of a gallery constructed in accordance with this invention showing one end gate in place. Fig. 2 is an enlarged perspective view of one end of the gallery showing the end gate being inserted in position.

Like numerals of reference indicate corresponding parts in each figure.

Referring to the drawings, 1 is a gallery 40 formed of a flat plate having the side flanges 2 preferably formed of lengths of angle iron.

45 3 are arc-shaped notches or slots cut in the upper edges of the side flanges 2 adjacent to the ends and extending downwardly and inwardly toward the center of the gallery.

50 4 is an end gate here shown formed of a length of angle iron having one of the flanges thereof formed with the lugs 5 projecting from the ends, said lugs being integral with the flange and formed arc-shaped extending downwardly from the top. The

55 lugs 5 are formed to fit snugly into the slots 3 in the flanges of the gallery when the end gate is in position closing the end of the gallery and the forwardly curved ends of said lugs hold the said gate securely from dislodgment vertically or horizontally.

60 In order to place the end gate in position it is merely necessary to insert the ends of the curved lugs in the ends of the slots and release the gate. The weight of the gate causes the curved lugs to follow the guiding slots and the gate drops to its closed 65 position.

65 It will be readily seen that the gate can only be removed by a tilting movement consequently when the type is fitted into the gallery against the end gate it can not possibly get out of place unless tilted from the outside and such a movement cannot occur accidentally.

70 The construction of the device is very simple and the end gate formed as shown 75 and described is very easily made and consists of only one piece of metal.

75 A very important feature in the present device is that the end gate may be used at either end of the gallery so as to accommodate 80 the arrangement of the type.

What I claim as my invention is:—

1. A printer's gallery having arc shaped notches cut in the top edges of the side flanges adjacent to the ends, and an end 85 gate adapted to fit between said side flanges and having rigid arc shaped lugs projecting laterally from the ends thereof and adapted to fit into said notches.

2. A printer's gallery having arc shaped notches cut in the side flanges adjacent to the ends and extending downwardly and inwardly from the top, and an end gate formed of a piece of angle iron having projections from one of the flanges split from 95 the bottom upwardly to a point adjacent to the top, the projecting portions being bent forwardly in arc shape and forming lugs adapted to extend into and fit snugly into the arc shaped notches in the side flanges. 100

Signed at Bristol, England, this twenty-eighth day of October, 1911.

ALFRED HENRY STOCKALL.
